Des. 184,053
Patented Dec. 9, 1958

184,053

TELEVISION RECEIVER

Emil I. Harman, Philadelphia, Pa., assignor to Philco Corporation, Philadelphia, Pa., a corporation of Pennsylvania

Application November 19, 1957, Serial No. 48,549

Term of patent 14 years

(Cl. D6—4)

FIG. 1.

FIG. 2.

The side of the television receiver not shown is substantially the same in appearance as the side shown.

I claim:

The ornamental design for a television receiver, substantially as shown and described.
